CANDLE HOLDER OR SIMILAR ARTICLE

Norman L. O'Brien, Somerset, Mass.

Application July 5, 1957, Serial No. 46,841

Term of patent 14 years

(Cl. D48—2)

FIG. 1

FIG. 2

FIG. 3

FIG. 4

Figure 1 is a perspective view of a candle holder or similar article, showing my new design.

I claim:

The ornamental design for a candle holder or similar article, as shown.
